BED AND CYLINDER PRESS FOR SUPER-POSED IMPRESSIONS

Gilard Kargl, San Antonio, Tex.

Application December 16, 1948, Serial No. 65,653

11 Claims. (Cl. 101—269)

1

This invention relates to printing presses and has specific reference to a press for color printing of graphic logs on long narrow strips of material to be printed.

It is a common practice now in the drilling of oil or other wells to keep a "Well Log," which gives a graphic record in colored transcription of the different strata of earth penetrated in the drilling operation. The geological departments of the oil industries consistently use such logs. Heretofore, the procedure in making the logs is to use colored ink or pencil applied by hand to a base form printed on a long narrow strip of paper marked off in intervals of drilling depth. One size of form used comprises a strip of paper approximately five feet long and three inches wide lined transversely over the length of the sheet at one inch intervals each representing 100 feet of well depth. A $\frac{5}{8}$ inch wide strip runs along the left side of the log, and this strip is subdivided into $\frac{1}{8}$ inch wide spaces, each representing ten feet of well depth.

Several copies of the well log are usually required, each an exact duplicate of the other. However, rarely are more than 10-20 copies of the well log required. It will be seen, therefore, that accurately preparing these copies by hand would be a painstaking, tedious and time consuming process, while a conventional press and operating it with sufficient accuracy for exact color registration would be prohibitive. Moreover, a conventional press, such for example as a proof press which is satisfactory for black printing, is inherently not sufficiently accurate in operation to give overprinting registration necessary for color printing of the type discussed. Attempts to use color photography and colored typewriting processes have proved unsuccessful. In short, the hand coloring of well logs has heretofore been better and cheaper.

Therefore, it is a primary object of this invention to provide a printing press for a multicolor process on an elongated strip of material to be printed and capable of correct multicolor registration.

Another object of this invention is to provide a press for printing an elongated strip of material having a paper supporting matte associated with accurate collimating means and clamping means for holding the material to be printed immovably in place throughout its length to insure against travel of the material during successive overprintings.

Another object of this invention is to provide a printing press having a press roll which is

2

geared to pass over said material to be printed in non-slipping contact so that successive colors may be printed on said material in correct color registration.

5 Another object of this invention is to provide a printing press for printing an elongated strip of material having at least one type holding chase in which the type is locked in position by lateral pressure so that the type will not move from its correct position during successive printings and so that vacant spaces may be left in the printing surface where desired.

Another object of this invention is to provide a printing press having at least one chase in which the type is easily set and held in transverse-cut slots.

Another object of this invention is to provide a printing press having two lift-out rollers which are readily removable to speed up the multicolor process and which when removed leave all the remaining rollers uncontiguous to facilitate cleaning.

Another object of this invention is to provide a printing press having an inking roller unit with contiguous rolls therein of different diameter so that each roll makes contact with its neighbor roll along a different line on each revolution to more evenly distribute ink and reduce roll wear.

Still another object of this invention is to provide a printing press for applying a multicolor process to an elongated strip of material to be printed which is easy to set up for operation and in which corrections may be readily made.

With these and other objects in view, reference is made to the accompanying drawings and detailed description thereof which is set forth for the purpose of explaining the invention in its preferred embodiment, but which is not meant to limit the scope of the invention except as defined in the appended claims.

40 In the drawings:

Fig. 18 is a fragmental plan view of an oil well log printed in the press of this invention.

In its broadest concept this invention embodies a printing press for printing a multicolor well log in correct color registration on an elongated strip of material to be printed. Means are provided for correctly registering each strip of material on a matte on the press and further means are provided for locking the material in place along its entire length on the matte. Type which is set in transverse cut slots in a chase to be used in the press is easily set and allows the chase and type to be locked in place by a member exerting lateral pressure along the entire length of the chase. A press roller unit is provided with mechanism whereby it contacts the printing matte when moved in only one direction and whereby the roll rotates at a peripheral speed equal to the movement along the matte to prevent relative movement of the paper to the type. An inking roller unit is provided with readily removable lift-out rolls for quick color changes and contiguous rolls of different diameter to insure even distribution of ink therein and means are included for alternately locking out the press roller unit and the inking roller unit as the matte is respectively positioned in a loading or a printing position.

Referring particularly to the drawings, Figures 1 and 2 show the printing press 10 of this invention in broken up longitudinal sections. An elongated frame 11 acts as a support for the press. Standards or bearing posts 12, preferably of bronze, are spaced at intervals along one side of the frame to carry a round rail 13 which is journaled for rotation on said standards. A gear rack 14 is carried on a rail 15 which is on the other side of the frame and parallel to the round rail. Together the round rail and the geared rail form a track 16. A press roller unit 17 is mounted for movement along the track 16 and is parked at one end of the press on said track when that unit is not in operation.

An inking roller unit generally designated as 75

23 is normally parked at the other end of the track from the press roller unit. This unit comprises a group of rolls and gears to be explained in detail in relation to Figure 8 later on. A lock-out 24 is fixed on the round rail to hold the inking roller unit in its parking position when it is not being used. Another lock-out 25 is fixed on the round rail in 180° opposite phase to lock out for the inking roller unit so that it may be moved over the central portion of the frame when the lock-out 24 is in position to hold the inking roller unit back. Note that the lockouts do not obstruct the entire circumference of the round rail, for when one lockout is turned downward, it leaves the rail free at that end of the track for the roller unit at that end to move along the frame.

Along the longitudinal center of the frame 11 and between the rails of the track is a printing press bed 26 for mounting at least one type carrying chase 27 as shown in Figure 5. A matte frame 28 having a matte 29 mounted therein is rigidly secured to and extends radially from the round rail to move with said rail as it is rotated. Ordinarily, the round rail is rotated in a 180° arc so that the matte moves from a horizontal loading position at the side of said frame 11 to a horizontal printing position over the bed 26. One or more arms 30 extend from the side of the frame 11 to support the matte when it is in the loading position.

The control mechanism

35 A handle operated mechanism 31 is positioned at the end of the round rail where the press roller unit is parked to actuate the round rail. This mechanism as shown in Figure 3 comprises a housing 32 from which extends a crank shaft 33 on which is fixed a crank arm 34 with a handle 35. A crank arm 36 is fixed to the inner end of said shaft 33. A gear wheel 37 is connected to the crank arm 36 through a gear crank 38. The gear 37 engages a gear 39 which is fixed to the round rail 13. When the handle 35 is in the position shown by the dotted lines, the matte is in the printing position over the bed of the printing press. Also, the lockout 24 holds the inking roller unit in its parking space. When the handle 35 is in the position shown by the dotted lines, the matte is in the loading position on the extending plate 30. In this position the lock-out 25 will hold the press roller unit in its parking space and the inking roller unit may be moved forward over the bed 26. It is to be noted that the gear crank 38 is positioned on the gear 37 by a pivot stud 38' in such location that when the matte is moved from one extreme position to the other, it moves through its intermediate position quickly but slows down to ease into the extreme positions gradually. This provision prevents wear and tear on the matte and provides the conventional slow approach to the type.

The matte and printing material clamp

As shown in the loading position in Figure 7, the matte frame 28 has an angle iron 40 along its inner side which is attached by bars 41 to the round rail 13. A similar angle iron 42 forms the outside edge of the matte frame. An end plate 43 connects the angle irons forming the sides of the matte frame. A rotary shaft 44 is disposed within the matte frame along each side thereof and journaled for rotation in the end plate 43. Finger clips 45 are arranged along said shafts at intervals to clamp a material to be printed in

place throughout the length of the matte on both sides thereof. The matte 29 includes a sheet metal base 46 with a rubber covering 47 for better receiving type impressions. Collimation pins or pegs 48 protrude from the rubber covering along one side of the matte at spaced intervals. The material to be printed is provided with holes along one side thereof to register with the collimation pins on the matte. Thus, all sheets of material to be printed placed on the matte will always be in the exact same position. With every sheet of the material to be printed placed on the matte in proper registration on the collimation pins and the finger clips lowered into contact with the material to be printed, every sheet will always be registered in the exact same manner on the matte and held throughout its length against movement out of such registration.

A toggle coupling 49 is located on the matte at the end thereof toward the inking roller unit and connects one rotary shaft of the matte with the other so that when one is turned to clamp down on the material to be printed the other will do so simultaneously. The coupling includes a crank arm 50 fixed to each shaft and a separate connecting bar 51 joining each crank arm to the opposite extremities of a centrally positioned plate 52 which is pivoted at its center 53 to the end plate 43.

On the end of the matte toward the extension plate 30, there is an end plate 54 journalling the ends of the shafts 44 as shown in Figure 10. The end plate 54 has an upward extension 55 through which passes a pivot bolt 56. A head 57 covers one end of said bolt and a cotter pin 58 in the other end holds the bolt against longitudinal movement. A latch 59 is carried by the bolt 56 in a slot 60 of the extension 55. A spring 59', shown in Figure 12, forces the bottom of the latch out from the slot 60. The latch is serrated on its upper edge for finger control if desired. A latch handle 61 is fixed to the end of the inner shaft 44 by a positioning screw 62 so that the shaft will turn when the handle is moved. The latch handle is slotted to receive an angular latch key 63 which is pivoted within the slot at 64 and has a projection 65 beyond the slot for hand operation. A spring 63' pushes the key to extend it out of the slot toward the latch. As shown in Figure 12, the key 63 fits into a recess 66 within the edge of the latch 59 to lock the latch handle in place. When the latch handle is down as in the locked position the finger clips on the shaft 44 are clamped down against the matte and a material to be printed placed thereon. The latch handle turns the inner shaft to which it is attached and that shaft in turn actuates the toggle coupling to turn the other shaft to the clamped position.

Though the material to be printed clamping mechanism just described can be operated by hand, it can also be operated automatically. The plate extension 30 of the frame 11 is bolted to the frame by a bolt 67. An angular control member 68 is pivoted to the extension 30 at 69 for limited movement thereon. The control member 68 has an angular surface on its extreme end at 70. A spring 71 gives resiliency to the control member when the member is contacted.

When the matte is returned to the loading position from the printing position, it swings in an arc so that the latch 59 contacts the end of the control member 68 at the end 70. A forward sloping edge 72 of the latch 59 slides along the end 70 and forces the latch back into the recess

60 against the spring 59'. The latch is thus moved away from the key 63 so that the latch handle is free. Since the key 63 protrudes from the inner side of the latch handle, the key is caught on the end 70 as the matte swings further down into the loading position. Thus the latch handle is suspended to keep the shafts 44 turned to a position which unclamps the clamping fingers thereon. To reclamp the clamping mechanism, the key 63 is actuated by hand operation of the projection 65 to remove the key from the surface end 70 of the control member. The latch handle then falls to the position shown in solid lines in Figure 10, the clamping position.

The press roller unit

The press roller unit shown in Figures 3 and 4 is contained in a housing 72. A press roll 73 is suspended within the housing on a pair of pivoted side plates 74 on either side thereof. An axle 75 runs through the roll 73 and is journaled in the side plates. The housing has a front gear wheel 76 and a rear gear wheel 77 on one side and normal wheels 76' and 77' on the other side. The front wheels are joined by an axle 78 and the rear wheels by an axle 79. The rear gear wheel 77 drives a gear 80 on a stud shaft 81. Another gear 82 on the stud shaft drives a gear 83 on the press roll axle to turn the press roll. These gears are arranged in a ratio such that the press roll will roll in non-slipping contact over the back of the matte as the press roller unit is pushed forward.

The side plate 74 on the gear side of the unit 35 is anchored on to the end of the stud shaft 81. The stud shaft is supported on its inner end by a positioning plate 84 which is bolted to an upper bar 85 and a lower bar 86. On the normal wheel side of the unit the side plate 74 40 is anchored by a through bolt 87 and a spacer ring 88 to the side of the housing. A lifting bar 89 is attached to the forward end of each side plate 74 to raise same. The upper end of each bar 89 is connected to a crank arm 90 which 45 is fastened by screws 91 to a bar 92. An operating lever 93 with a knob 94 is attached to the central portion of the bar 92 and extends through a slot 95 in the top of the housing.

The inking roller unit

The inking roller unit 23, as shown in Figure 8, has a carriage 96. The gears for driving and operating this unit are all arranged on one side thereof. A drive gear 97 is carried by a transverse axle 98 at the rear of the carriage. A wheel 99 on axle 98 as shown in Figure 7 supports the inking roller unit on the rail 13. A gear 100 is fixed to the axle 98 transmitting power from gear 97 to operate the rolls of the 60 unit as the inking roller unit is pushed forward on the track. The gear 100 meshes with a supply roll gear 101, which in turn meshes with a transfer roll gear 102. Gear 102 engages a large distribution roll gear 103 which drives a forward inking roll gear 110 and a rear inking roll gear 111 at the bottom of the carriage. An eccentrically mounted gear 112 at the front of the inking roller unit is normally disengaged from the gear rail, but is engaged with the gear rail 65 when the unit is pulled back to its starting place to raise the inking rolls from the type during the initial distribution of ink on the rolls and during cleaning. The axle 113 which carries the idler 112 carries an eccentric idler wheel and 70 handle (not shown) on its other end.

Figure 2 shows how the gears are supported by a longitudinal plate 114 held in spaced relation to the side of the carriage 96 by spacers 115 and bolts 116. A cross piece 117 joins the sides of the inking roller unit in front and a cross piece 118 joins same in the rear.

There are five rolls in the inking roller unit. A supply roll 119 carries the ink initially and transfers it to a transfer roll 120 which places ink on the distribution roll 121. The latter roll distributes ink to front and rear inking rolls 122 and 123 respectively for inking the type. The supply roll and the distribution roll are also lift-out rolls designed for easy removal for quick operation of the multicolor process. In Figure 9 one of the lift-out rolls has a fixed axle 124 borne by bearings 125 in the carriages 96 and the plate 114. A removable axle 126 is connected at one end for rotation with the fixed axle by a multi-jam coupling 127. The other end of the axle 126 is held in a detent 128 within the carriage. A steel ball 129 is forced outward from a tapered hole 130 by a spring 131 which is held by a screw 132. The ball is greater in diameter than the end of the hole so that it cannot come out. The end of the axle 126 is provided with a curved surface which engages a portion of the ball to hold the axle firmly but also so that it can rotate. By lifting on the axle 126 at the end toward the detent it is easily snapped out of the inking roller unit. When both lift-out rolls are removed, none of the rolls remaining in the unit are touching one another. This enables easy cleaning, saves ink, and in addition, prevents flats in the rolls when the unit is out of use. Note also that all gears remain engaged at all times even if the lift-out rolls are removed in order to expedite cleaning and prevent damage to gears in handling. All rolls have the same diameter as the gears which drive them so that they will contact each other without slipping against one another.

The type chases

The type and method of setting same for the printing press of this invention is shown in Figures 13-17. The chase block 27 of the color printing chase is preferably made of hard aluminum alloy into which are cut transverse slots 133. Steel spacers 134 are set into the slots. Clips 135 are punched into the steel spacers to secure them in a vertical position within the slot. A type slug 136 is used on the color chase. For printing spaces for descriptions on the log, numerals and transverse lines marking the 100 foot sections are printed by a type slug 137 which is employed in a description chase 138. Linotype slugs bearing the descriptive word of the well sample taken are inserted between the adjacent slugs 137 with furniture spacers inserted to fill in the blank spaces and hold the descriptive word slugs in firm printing position. Since no over-printings of the description chase are required, accurate registry of the words is not necessary. When printing in color, a furniture spacer occupies the space of the description chase.

Fig. 17 shows how the type 136 is adapted to give greater variation to the log by having symbols cut in its printing surface, and how the printing surface of the type may be partly cut away to show degrees of symbolizing. The type slugs are made to have some clearance between the spacers so that they may be set more quickly. A black log chase for printing the division lines between the ten-foot well depth intervals, and also for

holding black log type carries a type slug similar to the type 136, but the spacers are as high as the printing surface of the type.

The chase lock

A unique chase lock has been devised to lock these chases in the bed of the press frame. In Figures 6 and 7, the bed has the movable side 140 and a stationary side 140'. Soft material 141 lines the inside top and bottom of the movable side. Plates 142 are positioned at intervals along the outside of the movable side of the bed. A connecting arm 143 joins the plate 142 with a crank arm 144 which is fixed to a pivot shaft 145. The shaft 145 extends through the side of the frame 11 and has another crank arm 146 on its lower end. A connecting rod 147 connects all the crank arms 146 along the side of the frame 11 to actuate same in unison as a handle 148, as shown in Figure 1, is moved to apply the chase lock. Thus all chases and any furniture spacers which may be used are locked in one operation. Even pressure is applied throughout the length of the chases, and the individual type slugs are locked in place between the movable and stationary side of the bed. In this manner the type is not dislocated by longitudinal compression of the type from one end of the elongated chase to the other. In addition, any space in the log chases may be left vacant where no indication is recorded.

A sample of a geologic well log as produced by the printing press herein described is shown in Figure 18 with the numerals designating the depth of the well.

In accordance with the invention, the chases are compiled and then the appropriate chases are placed into the bed of the press and locked. The appropriate color of ink is applied to the supply roll of the inking roller unit. The inking unit is moved back and forth out of contact with the type and the ink is distributed evenly on the inking rolls due to the different diameter of the rolls.

The material to be printed or paper which has been appropriately perforated is placed on the matte in proper registration over the collimation pins and then the paper clamp locks it in place. The inking roller unit is brought into contact with the type and rolled back and forth over it once. The matte is closed and the press roller unit is pushed forward over the matte in contact with the same. As the press roller unit hand lever is pulled back for the return of the unit, the contact with the matte is broken, and the unit idles back to its parking space. When the matte is swung back to the loading position, the paper clamp is automatically opened on both sides of the paper and the log paper can be removed. The operation is then repeated for other printings. It is to be noted that by cutting the paper to be used with the grain running the long way and by perforating only the amount of paper to be printed at one run, greater accuracy in collimating the paper is achieved.

From the foregoing it is apparent that the press of this invention ensures the most correct color registration in the printing of a multicolor log on an elongated strip of material to be printed. Not only is the material to be printed carefully registered and clamped in place throughout its length, but the type is held firmly against dislocation throughout its length as well. In addition, the press roll is in contact with the matte while moving in only one direction to avoid travel of the matte over the type.

Furthermore, this printing press enables fast operation of a multicolor process. Not only may the type be set quickly, but spaces not needed may be left vacant. Also, the paper clamp is partially automatic to speed up the loading of paper. The lift-out rolls are readily interchangeable and the ink rolls are easily cleaned.

I claim:

1. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position from said bed, and means for rotating said round rail.

2. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position away from said bed, a gear rotated by a crank arm and engaging said round rail for controlling the position of the matte, said crank arm being positioned on said gear to move the matte slowly as it approaches the printing and loading positions respectively.

3. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position away from said bed, means for rotating said round rail, members on said matte for holding the printing material in proper registration on said matte, and means operable on said matte for clamping said printing material to the matte.

4. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position away from said bed, means for ro-

tating said round rail, means operable on said matte for clamping said printing material to the matte, a plate extending from the side of said frame to contact one end of the matte when in loading position and limit its movement, and a member on said plate for actuating said printing material holding means.

5. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position away from said bed, means for rotating said round rail, collimation pins protruding from the surface of said matte for holding the printing material in proper registration by engaging holes cut in said material and means operable on said matte for clamping said material to the matte.

6. A printing press comprising an elongated frame, a type supporting bed extending longitudinally thereof, a track extending the length of said frame above said bed, a press roller unit and an inking roller unit supported on said track, a matte for carrying a material to be printed, said matte hinged for a printing position over said bed and a loading position away from said bed, an end plate at each end of said matte, clamping bars journaled on each side of said matte in said end plates and having clamping fingers extending therefrom to clamp said printing material onto said matte along both sides thereof, a latch and a latch handle at one end of said matte for actuating one of said clamping bars, and means for actuating the other bar simultaneously with the actuation of the one bar.

7. A printing press comprising an elongated frame, a type supporting bed extending longitudinally thereof, a track extending the length of said frame above said bed, a press roller unit and an inking roller unit supported on said track, a matte for carrying a material to be printed, said matte hinged for a printing position over said bed and a loading position away from said bed, an end plate at each end of said matte, clamping bars journaled on each side of said matte in said end plates and having clamping fingers extending therefrom to clamp said printing material onto said matte along both sides thereof, a latch and a latch handle at one end of said matte for actuating one of said clamping bars, a crank arm on each bar at the other end of said matte, and a toggle coupling joining said crank arms to actuate each bar simultaneously.

8. A printing press comprising an elongated frame, a type supporting bed extending longitudinally thereof, a track extending the length of said frame above said bed, a press roller unit and an inking roller unit supported on said track, a matte for carrying a material to be printed, said matte hinged for a printing position over said bed and a loading position away from said bed, an end plate at each end of said matte, clamping bars journaled on each side of said matte in said end plates and having clamping fingers extending therefrom to clamp said material to be printed onto said matte along both sides thereof, a latch and a latch handle at one end

11

of said matte, said latch handle being secured to one of said clamping bars to actuate same, means for actuating the other bar simultaneously with the one bar, a plate extending from the side of said frame to contact the latch end of the matte when in loading position and limit its movement, and a control member on said plate for tripping said latch as the matte swings to the loading position in order to release the clamping fingers from the material to be printed.

9. A printing press comprising an elongated frame, a type supporting bed extending longitudinally thereof, a track extending the length of said frame above said bed, a press roller unit and an inking roller unit supported on said track, a matte for carrying a material to be printed, said matte hinged for a printing position over said bed and a loading position away from said bed, an end plate at each end of said matte, clamping bars journaled on each side of said matte in said end plates and having clamping fingers extending therefrom to clamp said material to be printed onto said matte along both sides thereof, a latch at one end of said matte, a latch handle having a latch engaging key associated therewith secured to one of said clamping bars at the latch end of the matte to actuate said bar, means joining said bars to actuate the other bar simultaneously with the one bar, a plate extending from the side of said press frame to contact the latch end of the matte when in loading position and limit its movement, a control member extending upwardly from said plate for tripping said latch as the matte swings to the loading position and holding said latch handle in a position to release the clamping fingers from the material to be printed.

10. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said rail and extending radially thereof so that it may be swung to a printing position over said bed and to a loading position

12

away from said bed, and means for rotating said round rail, and a lock out positioned toward each end of said round rail for first locking out the press roller unit and then the inking roller unit from movement over said bed as the matte is respectively moved from the locking position to the printing position.

11. A printing press comprising an elongated frame, a type supporting bed extending longitudinally thereof, a track extending the length of said frame above said bed comprising a pair of rails one on each side of the frame, one of said rails being of round cross section and journaled for rotation on the frame, a press roller unit and an inking roller unit supported on said track for alternate movement along said track over said bed, a matte for carrying a material to be printed attached to said round rail and extending radially thereof so that it may be swung to a printing position over said bed and to a loading position away from said bed, means for rotating said round rail, and a lock out positioned toward each end of said round rail for first locking out the press roller unit and then the inking roller unit from movement over said bed as the matte is respectively moved from the loading position to the printing position, said lock outs comprising wheel blocks secured to said rail in 180° opposite phase.
